HOLDER FOR A TOOTH PASTE TUBE AND TOOTHBRUSHES OR THE LIKE

Edward J. Strachan, 7262 S. Cales Ave., Chicago, Ill.

Filed Jan. 20, 1960, Ser. No. 59,114

Term of patent 14 years

(Cl. D4—3)

*Fig. 4*FIG. 1 is a front perspective view taken from the top and right side of a holder for a tooth paste tube and toothbrushes or the like embodying my new design, it being understood that the perforated pattern which is fragmentarily shown extends throughout the holder panels;

FIG. 2 is a front elevational view thereof;

FIG. 3 is a top plan view thereof; and

FIG. 4 is a rear perspective view thereof.

The dominant features of my design reside in the portions shown in solid lines in the drawings.

I claim:

The ornamental design for a holder for a tooth paste tube and toothbrushes or the like, substantially as shown and described.
